UNITED STATES PATENT OFFICE

2,577,728

BOILER

Carl Z. Alexander, Hopatcong, N.J.

Application November 10, 1948, Serial No. 59,375

1 Claim. (Cl. 122—408)

1

This invention relates to boilers adapted to the generation of steam for heating purposes or the like and further adapted to serve as the heat generating source of a hot water heating system.

In the evolution of the boiler, the trend has been to separate the water into as many communicating parts as possible and to apply heat to each of the parts in the most efficient manner possible.

It is an object of the instant invention to provide a boiler of the geyser type in which the efficiency is substantially increased over known types.

A further object is to provide a boiler adapted to respond more quickly to the application of heat than heretofore possible.

Other objects of the instant invention will become apparent in the course of the following specification.

In the accomplishment of these objectives, the boiler is formed with a fire box at the front of the base. A refractory wall forms the fire box and partially supports water walls which extend upwardly and communicate with each other and a lower horizontal water chamber in the floor of which is a downwardly directed water trough or drop water baffle. Above the lower water chamber in spaced parallel arrangement is an upper water chamber. Aligned with the water trough of the lower chamber is a nipple connecting the two chambers, the top of the nipple being extended upwardly in the upper chamber to maintain the water level therein. A geyser tube is secured in the water trough and extended upwardly within and above the rim of the nipple in the upper chamber so that the water agitated by the heat in the lower chamber is passed upwardly to the upper chamber, the excess water being returned to the lower chamber through the nipple as the level of water in the upper chamber exceeds a predetermined magnitude. The fire box is so designed that a baffle wall at the back but in front of the water trough of the lower water chamber will direct the products of combustion upwardly to the base of the lower chamber at the front and thence downwardly around the outside surface portion of the water trough toward the back of the lower chamber where an opening therethrough permits the products of combustion to pass upwardly to a space formed between the two chambers. Baffle plates and the flue outlet are so arranged in the space between the two chambers that the opposed surface portion of each chamber is thor-

2

oughly bathed with the products of combustion prior to passing out of the flue outlet.

The invention will appear more clearly from the following detailed description when taken in connection with the accompanying drawing showing by way of example a preferred embodiment of the inventive idea.

In the drawings:

Figure 1 is a view in perspective with part of the walls broken away to show the interior of the boiler constructed in accordance with the principles of this invention.

Figure 2 is a vertical sectional view of the boiler taken on line 2—2 of Figure 1.

Figure 3 is a view along the line 3—3 of Figure 2.

Figure 4 is a view along the line 4—4 of Figure 2.

Referring now in greater detail to the drawings in which like reference numerals indicate like parts, reference numeral 10 (Fig. 1) indicates the outer jacket, 12 the fire box, 13 the water walls communicating with a lower horizontal water chamber 14, 15 the upper horizontal water chamber, and 16 the geyser tube.

The fire box 12 may be made of refractory material having side walls of arcuate form as most clearly shown in Figure 1 and with a base member 20 (Fig. 2) of similar material. It will be noted in Figures 1 and 2 that the fire box 12 occupies only a portion of the bottom of the boiler at the front so that the refractory wall serves as a baffle in directing the heat as later shown. In the front of the fire box 12 is an opening 21 for the insertion of any suitable heat source 22 (Fig. 1).

Directly above the fire box 12 and partially supported thereby, are the communicating water walls 13 which may be formed with spaced parallel members 23 and 24 (Fig. 2) closed at the base and terminating in and communicating with the lower horizontal water chamber 14 as shown.

The lower chamber 14 is a substantially watertight hollow body formed with opposed side and end members as well as a cover and base and is designed to be fitted within the outer jacket 10, subsequently described. An opening in the front end of the chamber 14 removably covered by the plate 25 (Fig. 1) is provided for the removable insertion of a hot water supply coil 26 to furnish a domestic hot water supply, the ends of the coil 26 being connected through the plate 25 with the hot water system in a known manner. Along the bottom surface portion of the chamber 14 is a water trough 27 communicating with the cham-

ber 14. The trough 27 is placed intermediate the fire box 12 and the back of the boiler in order that the heat generated in the fire box will be directed upwardly against the base of the chamber 14 and thence downwardly and upwardly around the trough 27 to the flue opening 28 at the back which passes through the chamber 14 to direct the products of combustion to the passage way 29 formed between the chamber 14 and the later described upper chamber 15.

The upper horizontal water chamber 15 is disposed in spaced parallel relationship to the lower chamber 14 and is similar thereto except for the communicating water walls 13 of the lower chamber and the trough 27. Any suitable means may be used to maintain the upper chamber 15 in position and it may be so formed that the cover of the outer jacket 10 serves also as the cover for that chamber. Registering openings are made in the bottom surface portion of the upper chamber 15 and the top surface portion of the lower chamber 14, both of the openings being aligned with the water trough 27. A nipple 30 is disposed through the openings with the top extending upwardly into the upper chamber 15 to maintain the desired water level. Through the nipple 30, a geyser tube 16 is passed with the base thereof in the base of the water trough 27 and the top extending through the nipple 30 to a point above the upper rim as shown in Figure 1. Obviously, the registering openings between the two chambers and the nipple therebetween could be aligned over the length of the water trough 27 and a number of geyser tubes used.

Referring now to Figure 3, the top of the nipple 30 is shown and on one side of which at the back is a flue outlet 31 leading to a chimney (not shown). On the opposite side of the nipple 30 is the passageway 28 for the products of combustion passing through the lower chamber 14 as previously shown. Between the flue outlet 31 and the flue passageway 28 is a vertically disposed baffle plate 32 which completely closes the passageway 28 at that end. Extended forwardly of the nipple 30 is a coacting baffle plate 33 to direct the products of combustion over the opposed surface portions of the chambers 14 and 15 that is the ceiling of chamber 14 and the floor of chamber 15 before passing out of the boiler through the flue outlet 31.

Means are provided for withdrawing the generated steam from the top of the upper chamber 15 through the outlet 34. A flame inspection port 35 may be formed through the front wall of the fire box 12 and removably covered by the pivotally mounted member 36. In addition, means are provided for introducing water into the chamber and an opening at the front of the passageway 29 removably covered by the plate 37 may be provided for cleaning purposes.

The space between the lower chamber 14 and the upper chamber 15 is enclosed except for the previously mentioned openings by any suitable means supporting the upper chamber in spaced relation with the lower chamber.

The outer jacket 10 is formed with the spaced parallel front member 38 and back member 39, the side member 40 spaced parallel to a corresponding member on the opposite side (not shown) and in such a manner as to leave a working space at the front of the boiler. The cover member 41 completes the outer jacket 10 all of the members of which are joined along corresponding edges and the cover member 41 may be so secured over the top of the upper chamber 14

that a substantially steam tight closure results. The front member 38 is provided with a removable portion 42 for servicing the boiler and insulating material may be used between the sides and back of the inner components and the opposed surfaces of the jacket.

The operation of the boiler is as follows: Water is inserted in the upper chamber 15 until it is filled to the top of the nipple 30 whereupon the excess water spills through the nipple 30 to fill the water walls 13, the water trough 27, and lower chamber 14 to a level which may be regulated by any known means. The boiler filled and the water turned off, heat is applied in the fire box 12 by any known means. The generated heat rises to bathe the bottom surface portion of the lower chamber 14, the water walls 13, and the water trough 27 on passing toward the passageway 28, thence through the passageway 28 into the space 29 between the chambers where the baffle plates 32 and 33 direct the generated heat over the ceiling of the lower chamber 14 and the floor of the upper chamber 15 before passing out of the flue opening 31 to the chimney (not shown). By the use of the water walls 13 a highly efficient boiler is provided. By the use of the water trough 27, a portion of the water in the lower chamber 14 is in the path of the most intense heat giving rapid action to the geyser tube 16 in raising the heated water to the level of the upper chamber 15. The use of the baffle plates 32 and 33 insures the maximum heat transfer to both chambers 14 and 15. In the case of a stoker fired boiler, the water trough 27 serves as a fly ash separator which contributes further to a boiler requiring relatively slight maintenance.

Obviously, the boiler could be of other than rectangular shape and more than two water chambers could be used with a geyser tube extending upwardly from the lower to the adjacent higher except in the uppermost chamber. In the case of a plurality of water chambers, only the space between the two uppermost chambers need be provided with the baffle plates 32 and 33 since a passageway could be provided through alternate ends of adjacent chambers until the two uppermost are reached and assuming that the flue outlet is provided in the space between the two uppermost chambers. For these reasons, it is apparent that the illustrations shown above have been given by way of illustration and not by way of limitation and that the structures above described are subject to wide variations and modifications without departing from the scope or intent of the present invention, all of which variations and modifications are to be included within the scope of the present invention.

What is claimed is:

In a boiler having an upper horizontal water chamber, a passageway for the products of combustion below the upper chamber and a lower horizontal water chamber below the passageway with a fire box below and at the front of the lower chamber, the water chambers and the fire box and the passageway being enclosed, the water chambers further being interconnected through the passageway by a vertical nipple substantially along the longitudinal center line of the passageway and adjacent the rear wall thereof, the passageway further having an outlet to a flue through the rear wall and to one side of the nipple; the improvements comprising a second passageway for the products of combustion from the fire box through the lower water chamber to the first passageway, the second passageway being

positioned rearwardly of the transverse central plane of the nipple and on the side opposite the outlet to the flue in the first passageway, a baffle disposed in the first passageway between the nipple and the rear wall of said first passageway and intermediate the outlet to the flue and the second passageway inlet into the first passageway, and a second baffle disposed in the first passageway on the side of the nipple opposite to the first baffle and extending forwardly of the nipple, both baffles extending between the ceiling of the lower water chamber and the floor of the upper water chamber.
